UNITED STATES PATENT OFFICE.

EDWARD C. KELLINGTON, OF PORTLAND, OREGON.

SPOUT FOR MILLING MACHINERY AND GRAIN-ELEVATORS.

1,323,225.

Specification of Letters Patent. Patented Nov. 25, 1919.

Application filed April 15, 1919. Serial No. 290,169.

To all whom it may concern:

Be it known that I, EDWARD C. KELLINGTON, a citizen of the United States, residing at Portland, in the county of Multnomah and State of Oregon, have invented certain new and useful Improvements in Spouts for Milling Machinery and Grain-Elevators, of which the following is a specification.

- 10 The invention provides a novel spout or conduit for conveying flour, feed, grain or cereal from one container to another in the handling and transferring of such commodity as may be necessary according to the 15 desired manipulation. Spouts or conduits of textile have generally been used for this purpose and it is the object of the present invention to replace such textile spouts or conduits by metal spouts and to construct 20 the same in a manner, whereby they are self-clearing to prevent choking but which under ordinary conditions prevent any waste of the material being transferred or conveyed from one part to another.
- 25 The drawing illustrates a preferred embodiment of the invention. However, it is to be understood that in adapting the same to meet different conditions, various changes in the form, proportion, and minor details 30 of construction may be resorted to without departing from the nature of the invention as claimed hereinafter.

In the accompanying drawing,

Figure 1 is a vertical central section of a 35 spout or conduit embodying the invention.

Fig. 2 is a horizontal section on the line 2—2 of Fig. 2, looking upward, as indicated by the arrow.

Corresponding and like parts are referred 40 to in the following description and indicated in both views of the drawing by like reference characters.

The numeral 1 designates a screen or other part from which the flour, feed, grain or like commodity is adapted to be discharged and 45 2 represents part of a receiver into which the said commodity is delivered. Between these two parts 1 and 2 is disposed the spout or conduit constituting the present 50 invention.

A delivery tube 3 is secured at its upper end to the part 1 and depends therefrom and is provided at its lower end with a plurality of points 4 which are outwardly flared and 55 perform the office of agitators and deliverers. In the present instance the part 1 constitutes

a portion of a screen or like part which has a vibratory movement imparted thereto, hence the tube 3 which is connected to the part 1 receives a like vibratory movement, 60 thereby enabling the points 4 to act as agitators and deliverers.

A receiving member is connected to the part 2 and comprises a funnel-shaped body 5 and a tubular portion 6, the latter being 65 secured in any manner to the part 2. The lower end of the delivery tube 3 extends into the upper portion of the funnel-shaped body 5. A plate 7 rests loosely upon the receiving member and is provided with an 70 upstanding collar 8 which loosely receives the lower portion of the delivery tube 3. The plate 7 constitutes a closure for the upper end of the receiving member and by reason of its connection with the tube 3 it 75 receives a corresponding vibratory movement. To obviate any noise and to insure a close fit the upper end of the receiving member is provided with a flexible lip 9 which preferably consists of a band of 80 leather secured to the upper edge of the body 5 and projecting a short distance thereabove.

In the practical operation of the invention it is assumed that the delivery tube 3 is 85 attached to a screen 1 and the receiving member is connected to a bin 2. The commodity discharged from the screen 1 passes through the tube 3 into the body 5 of the receiving member, thence through the tube 90 6 into the bin or like part 2. The plate 7 follows the movements of the delivery tube 3 by reason of its collar 8 having a telescoping fit on the tube 3. The plate 7 likewise closes the receiving member. Should the 95 spout or conduit tend to choke from any cause and the receiving member fill to overflowing the elements 5 by reason of their formation and connection with the delivery tube 3 agitate the commodity in the upper 100 portion of the body 5 and at the same time impart an outward and upward movement to the commodity with the result that the plate 7 is elevated and the surface material is caused to overflow the receiving member 105 and automatically discharge therefrom, thereby preventing choking of the screen 1 and at the same time giving warning by calling attention to the fact that the particular spout or conduit is not working 110 properly so that the difficulty may be remedied. The dotted lines in Fig. 1 illus-

trate the position of the plate 7 when elevated and the arrows show the direction of the commodity when automatically discharging from the receiving member of the 5 spout or conduit.

The foregoing description and the drawing have reference to what may be considered the preferred, or approved form of my invention. It is to be understood that I 10 may make such changes in construction and arrangement and combination of parts, materials, dimensions, etc., as may prove expedient and fall within the scope of the appended claims.

Having thus fully described my invention, what I claim as new and desire to 15 secure by Letters Patent is:

1. A conduit, substantially as herein specified, the same comprising a delivery tube 20 provided at its discharge end with flaring elements constituting agitators and deliverers, a receiving member having a flared portion into which the discharge end of the

delivery tube projects a short distance and a plate closing the flared end of the receiving 25 member and having a telescoping connection with the delivery tube.

2. A conduit of the character specified, the same comprising a delivery tube provided at its discharge end with a plurality 30 of flared elements constituting agitators and deliverers, a receiving member having a flared portion into which the discharge end of the delivery tube projects a short distance, a flexible lip at the upper edge of the 35 receiving member, and a plate resting loosely on the flexible lip and constituting a closure for the receiving member and having a loose connection with the said delivery tube. 40

In testimony whereof I affix my signature in presence of two witnesses.

EDWARD C. KELLINGTON.
